UNITED STATES PATENT OFFICE.

ANTON SOLMAN AND STANLEY SCHROEPFER, OF PITTSBURGH, PENNSYLVANIA, AS
SIGNORS OF TWO HUNDRED AND SIXTY-THREE THREE HUNDRED AND FIFTIETHS
TO SAID SOLMAN AND EIGHTY-SEVEN THREE HUNDRED AND FIFTIETHS TO SAID
SCHROEPFER.

REPEATING DEVICE FOR PHONOGRAHS.

Application filed October 23, 1923. Serial No. 670,323.

To all whom it may concern:

Be it known that we, ANTON SOLMAN and STANLEY SCHROEPFER, citizens of the United States, and residents of Pittsburgh, in the county of Allegheny and State of Pennsylvania, have invented a new and useful Improvement in Repeating Devices for Phonographs; and we do hereby declare the following to be a full, clear, and exact description thereof.

Our invention relates to devices for causing a phonograph to repeat the playing of records, and one of its objects is to provide a simple and effective device of this character which shall be inexpensive in construction and shall be neat and attractive in appearance. Another object of our invention is to provide a repeating device of the character indicated which shall be capable of adjustment to adapt it to phonographs of different kinds and to records of different sizes.

In the accompanying drawing, Fig. 1 is a plain view of a portion of a disc record in position on the turn-table of a phonograph, together with a repeating device constructed in accordance with our invention; Fig. 2 is a similar plan view showing the position of the parts at the time when the needle is released from the guide and is allowed to engage the screw shaft; Fig. 3 is an enlarged bottom plan view of our repeating device; Fig. 4 is an enlarged cross sectional view through the repeating device, the section being taken substantially on the line 4-4, Fig. 1; Fig. 5 is a fragmentary view, partly in vertical section and partly in side elevation, showing the adjustable construction of the guide and the manner in which the screw shaft returns the needle to the starting position, the section being taken substantially on the line 5-5, Fig. 1; and Fig. 6 is an enlarged transverse section through the casing and screw shaft showing the adjustable connection between the pivot member and the casing, the section being taken substantially on the line 6-6, Fig. 1.

As shown in the drawing the device consists of four main parts, a casing or body 2, a screw shaft 3, a needle gage 4, and an adjustable pivot member 5.

The casing 2 is suitably stamped, pressed or otherwise formed from a single piece of metal and is provided at its opposite ends

with bearings 6 and 7 to receive the ends of the screw shaft 3. The end of the casing 2 adjacent to the bearing 7 is widened as shown at 8 to form a flat bearing surface which prevents undue tilting of the device. This wide portion 8 is provided with an opening 9 through which extends the edge 60 of a friction roller 10 which is carried by the screw shaft 3.

The shaft 3 has a screw-threaded portion 11 of sufficient length to span the record band of the largest standard size of disc phonograph records. The remainder of the screw shaft may be left plain, and the casing 2 is preferably so shaped as to enclose the plain or inactive portion of the shaft 3 with a housing, as indicated at 12.

The lower edges of the casing 2 adjacent to the housing portion 12 are slightly flared outwardly as shown at 15, Figs. 5 and 6, to form guideways for the pivot member 5 which has an undercut slot 14 fitting over the housing so that the pivot member may be adjusted lengthwise of the housing to adapt the device to phonograph records of different diameters. The pivot member 5 is provided with an extension 16 having an opening 17 of suitable size to fit over the usual pin which projects upwardly from the center of the turn-table of a disc phonograph. Such a pin is indicated at 18, Figs. 1 and 2.

The end of the housing 12 opposite to the roller 10 is widened as shown at 20 and is provided on its under surface with a shoe 21 of friction material as shown in Fig. 5. This shoe is intended to rest on the plain portion of a record 22 between the record band and the outer edge of the record, and the friction set up between the record and the shoe 21 tends to move the screw threaded portion of the device downwardly as shown 95 in Figs. 1 and 2, this movement, however, being prevented when the needle of the phonograph engages the needle guide.

The needle guide 4 is composed of two parts, a stationary member 23 and an adjustable member 24. Both of these members are suitably provided with projecting portions of celluloid, horn or other similar material, this construction being best shown in Figs. 3 and 5 where the fixed member 23 carries a strip 25 secured to its under sur-

face by means of rivets or the like, while the adjustable member 24 carries a similar strip 26 secured to its upper surface by means of rivets or the like. The adjustable member 24 of the needle guide is secured to the casing 2 by means of a member 28 which, as best shown in Fig. 4, has an undercut slot which fits over the beveled edges 15 of the casing member 2. By adjusting the member 24 lengthwise, the effective length of the needle guide may be varied to suit records of different sizes.

The stationary portion 23 of the needle guide has a notch 29 formed opposite to the end of the screw shaft 3. This notch should be adjusted to the outer edge of the playing portion of the record, and serves to guide the needle to proper position on the record when the needle leaves the screw shaft 3 on its return movement.

In operation, the disc record which is to be played is placed on the turn-table and fitted over the central pin 18. If the pivot member 5 is not in the proper position on the casing 2 to bring the outer portion 20 of the repeater upon the smooth outer portion of the record, the pivot member 5 is adjusted lengthwise of the casing 2 to bring the portion 20 to the proper position. Also, the effective length of the needle guide is adjusted so that the needle will run off the inner end of the needle guide just after it has finished playing the record. When these adjustments have been made, the ring 35 of the pivot member 5 is placed over the pin 18 and the turn-table is started. The needle 30 is placed upon the record at the outer edge of the record band, at which time the needle occupies the notch 29 in the needle guide, and takes the position shown in dotted lines at the right of Fig. 5. The rotation of the disc in contact with the friction wheel 9 rotates the screw shaft 3 continuously, and when the needle reaches the end of the record band and runs off the inner edge of the needle guide, the frictional engagement between the under side of the enlargement 20 and the surface of the record causes the entire repeating device to swing in a clock-wise direction, Figs. 1 and 2, until the needle 30 is engaged by the screw shaft 3 as shown in Fig. 2. Thereupon the rotation of the shaft 3 causes the needle to move to the right as seen in the drawing, (see particularly Fig. 5) the needle being guided by the screw threads on the shaft 3 until the needle reaches the end of the screw-threaded portion of the shaft, whereupon the small unthreaded portion 32 at the outer end of the shaft 3 gives the needle an impulse or kick, which returns the needle to the notch 29 and brings the needle again into contact with the record at the beginning of the record band. This operation continues as long as the turn table is

driven, and the sound box and tone arm of the machine are of course carried back and forth with the needle.

We claim as our invention:

1. A repeating device for phonographs comprising a screw shaft, means for rotating said shaft, means for guiding a phonograph needle adjacent to said screw shaft while said needle is in reproducing contact with a record, means for then causing said needle to engage said screw shaft, thereby causing said screw shaft to return said needle to its starting position, a pivot member for mounting the device upon the central pin of a phonograph turn-table, and means for adjusting the said pivot member lengthwise with respect to said screw shaft. 70

2. A repeating device for phonographs comprising a screw shaft, means for causing the shaft to be rotated by means of a rotating phonograph disc record, and a needle guide adjacent to said screw shaft, said guide being adapted to maintain the phonograph needle out of contact with said screw shaft while said needle is in playing 80 engagement with said record, and being adapted to release said needle when the needle reaches the end of the playing portion of the record, whereby the said screw shaft returns said needle to its starting 95 position. 85

3. A repeating device for phonographs comprising a needle-returning screw shaft, a friction wheel on said shaft for rotating the same, means for mounting the shaft in position that said wheel will engage a rotating record and be driven thereby, and means for effecting engagement between a phonograph needle and said screw shaft when the needle has moved a predetermined distance 100 along the record. 105

4. A repeating device for phonographs, comprising a needle-returning shaft, a supporting bracket for said shaft, a perforated lug on said bracket for pivotal connection 110 to a turn-table post, a friction wheel on said shaft in position to be engaged and driven by the record when said bracket is connected to said post, and means for effecting engagement between a phonograph needle and said screw shaft when the needle has moved a predetermined distance along the record. 115

5. A repeating device for phonographs, comprising a needle-returning screw shaft, a supporting bracket for said shaft, means for effecting a pivotal connection between said bracket and a turn-table post, a friction wheel on said shaft in position to be driven by a rotating record, a friction member on said bracket at a point removed from said wheel and in position to seat upon the record, means for preventing movement of said bracket with the record while the needle is moving across the face of the 120 125 130

record, and means for permitting the shaft to move into engagement with the needle when said needle has traveled a predetermined distance.

- 5 6. A repeating device for phonographs, comprising a needle-returning screw shaft, a friction wheel on said shaft for rotating the same, means for mounting the shaft in position that said wheel will engage a rotating record and be driven thereby and to the rear of a phonograph needle, means for

yieldably advancing said shaft toward the needle, and means for permitting said shaft to engage said needle when the needle has reached a predetermined point in its path 15 of travel across the record.

In testimony whereof we, the said ANTON SOLMAN and STANLEY SCHROEPFER, have hereunto set our hands.

ANTON SOLMAN.
STANLEY SCHROEPFER.
